PRODUCTION OF HYDROCARBON FUELS

Arthur E. Pew, Jr., Bryn Mawr, Pa., assignor, by
mesne assignments, to Houdry Process Corporation,
Wilmington, Del., a corporation of Delaware

Application December 19, 1936, Serial No. 116,699

10 Claims. (Cl. 196—49)

The present invention relates to the art of treating fluids, especially hydrocarbon fluids. More particularly the invention involves the treatment of composite hydrocarbon fluids having a wide or substantial boiling range and derived from petroleum, coal, shale or other origin, natural or artificial.

My invention is concerned with transforming or converting such raw hydrocarbons or charge, for example, crude petroleum oil or topped crude, into lower boiling hydrocarbons, in the carrying out of which catalytic and pyrolytic operations, and apparatus therefor, are employed in inter-dependent relationship and in such combination that advantages and economies, both in process and apparatus, are thereby secured.

The charge to the system, e. g., crude petroleum oil, topped crude or the like, is divided into a plurality of fractions: (1) a high boiling or residual fraction, (2) a lower boiling fraction comprising components within the gas oil boiling range and/or the naphtha boiling range, and (3) especially where the charge is a whole crude, an overhead fraction comprising straight run gasoline, especially the lower boiling components thereof, and hydrocarbon gases. An additional fraction (or fractions) of boiling range intermediate the residual fraction and the aforesaid lower boiling fraction may, if desired, also be separated from the charge, and treated catalytically, or, especially where the aforesaid lower boiling fraction comprises a naphtha, rather than a gas oil, it may be treated pyrolytically rather than catalytically, if desired. These fractions (exclusive of the overhead gasoline fraction, which may be treated as desired) are treated catalytically and pyrolytically, the heavy or residual fraction being treated catalytically and the aforesaid lower boiling fraction being treated pyrolytically, and the synthetic crudes or products of each of such conversion operations are passed into a common separating zone or fractionating column, preferably without any recycling, up to this point, between the catalytic and pyrolytic operations. A relatively low amount of steam, or the like, is required with the hydrocarbons treated in the catalytic zone. A residual or heavy fraction or fractions and possibly one or more side stream fractions may be withdrawn from the products separator or synthetic crude column and subjected to a further pyrolytic conversion, or, according to a permissible mode of operation one or both of these recycle fractions may be catalytically treated or converted. But blending of the catalytic and pyrolytic synthetic crudes is ef-

fected preliminary to the further conversion or cracking of partly converted materials. The products of this latter conversion operation or operations may, if desired, be introduced into the aforesaid products separator or fractionating column and separated into fractions along with the aforementioned catalytic and pyrolytic synthetic crudes. The zone or zones for handling recycle from the products fractionator or separator may be separate from or the same as those which receive and convert fractions coming from the crude tower. However where, for example, a fraction from the products fractionator, which it is desired further to convert pyrolytically, is of a higher or substantially different boiling range than the fraction from the crude tower which is being pyrolytically converted, then it is ordinarily preferable separately to convert such recycle fraction. This would be the case, for example, where the lower boiling fraction from the crude fractionator consisted of a naphtha, e. g., a heavy naphtha, to be pyrolytically treated or reformed, whereas the fraction from the products fractionator which it was desired further to convert was in the gas oil boiling range, e. g., intermediate boiling range gas oil.

According to a preferred aspect of this invention the catalytic zones or converters handle only virgin stock or a previously untreated fraction of the charging material while the pyrolytic zone handles virgin distillate, once catalytically cracked material and recycle stock from products of pyrolytic conversion. The insufficiently converted fraction or fractions of the products of catalytic conversion are, however, as above indicated, preferably not sent directly to a pyrolytic zone or zones. Rather the synthetic crudes of both catalytic and pyrolytic conversion are blended together, for example in the products fractionator, and then a fraction or fractions are separated out and sent to a pyrolytic conversion zone.

The type and proportions of fractions separated by the crude tower or fractionator for charge and sent respectively to catalytic and pyrolytic zones are regulated so as to control the desired final product or gasoline withdrawn from the products separator or fractionator. Without changing the conditions of operation of the catalytic and pyrolytic units to substantial extent, by controlling the character and relative amount of charge to each, a hydrocarbon product or gasoline having controlled characteristics and comprising a relatively stable blend of pyrolytically cracked gasoline, catalytically cracked gasoline,

reformed naphtha and/or straight run gasoline, is produced. By such control the boiling range characteristics and octane or antiknock rating of the products can be regulated as desired and, at least with most charging materials, the sulfur content can be held within predetermined limits, except for the possible necessity of removing some hydrogen sulfide present in the products issuing from the products fractionator. The fraction or fractions sent to the catalytic zone or zones contains a substantial portion and often most of the sulfur content of the original charging material and the catalyst employed, in addition to performing its principal function of transforming higher boiling hydrocarbons into lower boiling hydrocarbons, converts combined sulfur, for example mercaptans, into hydrogen sulfide and/or retains the sulfur as a sulfurous deposit on the catalyst. The catalyst used comprises silicious material, for example an activated hydrosilicate of alumina or a blend of silica and alumina, preferably in molded form of cylindrical or annular shape for example, as illustrated in Patent No. 1,837,971, issued to Alfred Joseph on December 22, 1931, or in modified compositions as illustrated in the copending applications of Eugene J. Houdry, Serial No. 600,581, filed March 23, 1932, which issued on May 4, 1937 as Patent No. 2,078,945 or Serial No. 35,101, filed August 7, 1935, 30 which issued on May 4, 1937 as Patent No. 2,078,951.

In addition to the advantages set out hereinabove, it is a further object of this invention to provide for a high percentage conversion of higher boiling hydrocarbons into lower boiling hydrocarbons, such as gasoline. The steps of process are arranged and elements of apparatus are combined so as efficiently to produce a high quality product of controlled characteristics while effecting heat economies and economies of equipment. In a preferred aspect of this invention it is arranged to simultaneously employ both catalytic and pyrolytic operations in producing a desired motor fuel or gasoline while sending only virgin stock as charge to the catalytic conversion zone. It is also an object of this invention to minimize or avoid treating the final product or motor fuel for the elimination of organic sulfur (i. e., sulfur united in a molecule with carbon and hydrogen) while producing a product of other desired characteristics, from which, however, hydrogen sulfide may or may not be removed. It is an object of this invention to produce a motor fuel of suitably high octane rating at a low cost while preferably avoiding the recycling of a heavy fraction or fractions of the catalytic synthetic crude back to a catalytic conversion zone. Other and more specific objects and advantages will appear from the description which follows.

Important characterizing aspects of this invention are: (1) relatively low consumption of steam in effecting catalytic conversion; (2) passage of products of catalytic conversion, or at least a large part thereof, directly to the products fractionator without first condensing the same; (3) partially converted materials are converted further only after catalytic and pyrolytic synthetic crudes or products are intimately blended together; and (4) a fairly long boiling range fraction is normally sent to the catalytic conversion zone. The last-mentioned point of characterization is, in certain respects, closely allied with the point first mentioned.

For a ready understanding of illustrative aspects of this invention, reference is had to the

apparatus indicated in the accompanying drawings in which:

Fig. 1 shows diagrammatically the assemblage of apparatus, including catalytic and pyrolytic converters, a tower for preparing charge and a fractionator or separator for receiving products, as well as other elements of apparatus, connected in a particular and interdependent relation, to provide a complete commercial apparatus for making motor fuel, gasoline or the like from higher boiling hydrocarbons;

Figs. 2, 3 and 4 are modifications of the apparatus shown in Fig. 1.

Referring more in detail to the drawings, in the several figures of which like reference characters denote similar parts, 1a, 1b, 1c and 1d, appearing in Figs. 1, 2, 3 and 4 respectively, are columns or fractionators for receiving the unrefined hydrocarbons or charging material; 2a, 2b, 2c and 2d, appearing in the same respective figures, are products towers or rectifying columns for receiving products of conversion and separating out desired product or motor fuel therefrom. 3a and 4a, 3b and 4b, 3c and 4c, and 3d and 4d are converters, each of which contains a bed of contact mass or catalyst, for example a blend of silica and alumina of the type and in the form hereinabove described. In the operation of such catalytic converters, the reaction chamber of each may, for example, be maintained at a temperature of the order of 75° to 925° F., e. g., 850° F. and a pressure of atmospheric to 75 lbs./sq. in., preferably near atmospheric. A feed rate of 8/20 (8 liters of oil per hour per 20 liters of catalyst) to 20/20, e. g., 16/20, is suitable, although higher or lower rates may successfully be used.

An illustrative operation will first be described by specific reference to Fig. 1 of the drawings. The starting material or charge will, by way of example, be considered to be a whole crude petroleum oil. The incoming charge passes through heat exchanger 5a and then through heater 6a into fractionating column 1a, where the charge is divided into several fractions. An overhead fraction comprising gasoline and hydrocarbon gases is withdrawn from the top of crude tower 1a, as shown. A residual fraction is withdrawn from the bottom of tower 1a and is forced by pump 7a through heater or viscosity breaker 8a in catalytic zone B1. During passage through 8a steam or the like in small amounts may be introduced with the residual hydrocarbon fraction to control the viscosity breaking operation as desired. Products from viscosity breaker 8a pass to tar separator 9a where heavy, unvaporized components are removed and withdrawn through line 10a. Overhead from the tar separator passes to one or the other of catalytic converters 3a or 4a.

Under ordinary conditions of operation at a given time only one of the converters 3a or 4a is in stream effecting the desired catalytic conversion or reaction, while the other converter is undergoing regeneration, a regenerating medium, such as air, being fed to said converter undergoing regeneration through one of the lines 26 or 27 while the products of regeneration are removed through the other of said lines.

A second fraction, which is to be catalytically converted in zone B1 and which is substantially free of components which cannot readily be vaporized without thermal cracking, is withdrawn as a side stream from column 1a through the line shown and is forced by pump 11a through heater 12a, in which a minor amount, if any, viscosity

breaking may be carried out. This fraction may have an end boiling point of the order of 725° to 800° F., e. g., 750° F. Steam in small amounts may be introduced into this side stream fraction while the same is passing through the heater 12a through the valved line shown, if desired, although this is ordinarily not necessary. The heated fraction leaving the heater 12a may be passed directly to one or the other of catalytic converters 3a or 4a or, permissibly, may be passed through valved line 13a into and through the tar separator, though this latter operation is seldom employed except to control the removal of tar or unvaporizable components from the residual fraction. In any event this fraction is combined with the tar separator overhead of the residual fraction and minimizes the amount of steam required to keep the latter in a suitably vaporous condition.

Products of reaction from catalytic converters 3a or 4a pass, without condensation, directly to the rectifying column or products fractionator 2a.

A lighter side stream fraction, consisting for example of a heavy or light naphtha having a boiling range up to about 550° F. for example, with an initial boiling range of about 250° F. or higher, is withdrawn from tower 1a through the line shown and passed to pyrolytic zone A1 comprising heat exchanger 14a and pyrolytic converter 15a. The pyrolytic converter or still may be maintained at a temperature of 750° to 1200° F. and a pressure of atmospheric or slightly below to 2500 lbs./sq. in. or higher. The products from the pyrolytic converter pass into vapor separator 16a where heavy carbonaceous or unvaporizable components are separated from the remaining vapors, the latter passing in heat exchange with the incoming charge to the pyrolytic zone through heat exchanger 14a and thence into products column 2a along with the catalytic synthetic crude from converter 3a or 4a. The reaction which takes place in the pyrolytic still is one of cracking or converting materials heavier than gasoline into products of the gasoline boiling range and/or of thermally reforming naphtha to improve its antiknock characteristics.

The blended pyrolytic and catalytic synthetic crudes are fractionated in tower 2a, from which an overhead fraction consisting of the desired product or gasoline is withdrawn and from which a residual fraction is withdrawn and forced by pump 17a through a second pyrolytic zone A1 comprising pyrolytic converter or cracking still 18a and a vapor separator 19a where high boiling or carbonaceous liquids are withdrawn from the remaining vapors and the latter are passed in heat exchange with incoming charge in exchanger 5a and thence into the fractionating column 2a.

The apparatus illustrated in Figs. 2, 3 and 4 as well as the general operation of each, will be generally understood from the description given in connection with the apparatus illustrated in Fig. 1 and the similar indication of like parts in the different figures. For example, capital letters followed by the numerals 2, 3 and 4 indicate the pyrolytic and catalytic zones while numerals followed by the letters b, c or d in Figs. 2, 3 or 4, respectively, are similar to the parts designated by the same numeral and followed by the letter a in Fig. 1.

However, as distinguished from the apparatus shown in Fig. 1, in that shown in Fig. 2 only one fraction is withdrawn from adjacent the bottom of the crude tower, as will be noted. Also the side stream fraction, withdrawn from tower 1b

and forced by the pump shown through heat exchanger 21 and thence, together with any desired volume of side stream fraction shown from products column 2b, into and through pyrolytic converter or still 15b, may have a higher boiling range than the upper side stream fraction of Fig. 1. For example, the side stream fraction of Fig. 2 may have an end boiling point of the order of 575° to 650° F., e. g. about 600° F. The outgoing products of the pyrolytic conversion zone A2 pass in heat transfer relation with the incoming feed to the system in exchanger 20, or with any portion thereof, as desired, and then flow through the line shown into an intermediate point in products column 2b, below the point at 15 which a side stream fraction may be withdrawn therefrom. The side stream fraction withdrawn from column 1b in Fig. 2 is of an average boiling point intermediate that of the two side stream fractions withdrawn from column 1a in Fig. 1 and may be considered as containing components in the light gas oil as well as the naphtha boiling range. Also, the problem of heat economy or heat transfer is handled quite differently in the apparatus of Fig. 2 from that shown in the apparatus of Fig. 1. In Fig. 1 the catalytic synthetic crude passes directly into the products fractionator while in Fig. 2 it first passes in heat exchange relation with the side stream fraction from the crude tower so as to help to bring that fraction to a temperature suitable for pyrolytic conversion. Also the fresh charge to the system in Fig. 2 passes in heat exchange relation both with the catalytic synthetic crude and the pyrolytic synthetic crude in heat exchangers 22 and 20, respectively.

The apparatus shown in Fig. 3 differs from that shown in other figures of the drawings in that a residual fraction from the products column 2c is passed, along with the lower side stream fraction from crude tower 1c through heater 12c of catalytic zone B3 and finally through catalytic converter 3c or 4c. The apparatus of Fig. 3 also provides for withdrawing a light side stream fraction from the products tower 2c and passing it, as well as a side stream fraction from the crude tower of like or similar boiling range to pyrolytic zone A3 and through converter or still 15c. The outgoing vapors from the pyrolytic converter shown may pass in heat exchange with the incoming feed or charge to the system in heat exchanger 20c. Then the pyrolytically converted products pass through the line shown and enter the products column 2c at or near the same level that catalytic synthetic crude is passed thereto. The catalytic synthetic crude, en route to the tower 2c, passes in heat exchange with the incoming charge or with any desired portion thereof in heat exchanger 22c. While the apparatus of this figure has the advantages pointed out, it does have the disadvantage that the higher boiling or residual fraction from the products column 2c is passed through the catalytic converter shown. That is, in this case the catalytic conversion zone is forced to handle, to some small extent, material other than virgin stock.

Fig. 4, in distinction to the other figures of the drawings, illustrates a type of operation where the catalytic synthetic crude is cooled by heat exchange with incoming charge in exchanger 22d so that a part, i. e., the highest boiling part of the catalytic synthetic crude from zone B4 is condensed from the remaining vapors. This high boiling part or condensate is then forced by pump 31 through line 24 to be used selectively as make-

- up material for the charge to zone A4 or some or all of it may be sent by line 25 into cooling, reaction arresting or quenching zone indicated at 30 to serve as a cooling or quenching medium for 5 vapor phase, thermally cracked synthetic crude in pyrolytic zone A4, thereby to arrest further thermal conversion and hence to avoid undesirable secondary reactions in the pyrolytic synthetic crude.
- 10 The apparatus of Fig. 4 is dissimilar to that shown in Figs. 1 and 3 especially in that only one side stream fraction is withdrawn from crude tower 1d, somewhat similar to Fig. 2, although the side stream fraction in Fig. 4 may be generally of lower boiling range than in Fig. 2. However the boiling range of the side stream fraction may be controlled by selecting distillate through either of the branch lines shown, as desired, as well as by controlling the operation of the tower.
- 15 Further, the catalytic synthetic crude is passed only in heat exchange with incoming charge before entering the products tower 2d and does not pass both in heat exchange relation with the side stream fraction from the crude tower as well as 20 with the incoming charge, in the initial stage of heat exchange of the latter, as in the apparatus of Fig. 2. Another respect in which the apparatus of Fig. 4 differs from that shown in the other figures is the structure provided for controlling the temperature of the lower end of the 25 products tower. A residual fraction may be withdrawn from products tower 2d and any desired portion thereof passed through cooler or heat exchanger 28 and thence forced by pump 29 back 30 into the column 2d, for example at a point above that at which the pyrolytic synthetic crude is introduced into the products fractionator and at a point below that at which the partially converted side stream fraction may be withdrawn 35 from the products fractionator.
- 40 It will be noted that Figs. 3 and 4 include a showing of a condenser C and gas and water separator D in circuit following the products fractionator for recovering the desired product from the overhead of the products fractionator.
- 45 This invention discloses an operation in which there is a very high conversion of crude charge into gasoline or light motor fuel, while keeping down steam consumption for catalytic conversion 50 to a low point. For example, the steam consumed may be kept well under 10% by weight of the charge to the catalytic converters, and may be down to 5% thereof, or lower, depending upon the average boiling point or average molecular 55 weight of material going into the tar separator.
- What I claim is:
1. In the production of lower boiling hydrocarbons from hydrocarbon charge composed to substantial extent of higher boiling hydrocarbons, the steps which comprise dividing the charge into at least two fractions of different boiling ranges, a lower boiling fraction and a higher boiling fraction, said lower boiling fraction being composed substantially of components at least as high boiling as gasoline, passing said higher boiling fraction through a catalytic reaction zone maintained under conditions capable of effecting a transformation thereof into lower boiling hydrocarbons of high anti-knock rating 60 and containing solid catalytic material capable of promoting the said transformation, passing said lower boiling fraction through a pyrolytic conversion zone while maintaining such fraction under pyrolytic conversion conditions so as to effect a substantial conversion thereof into chem-

ically different hydrocarbon compounds of improved anti-knock characteristics, blending products of the catalytic and pyrolytic conversions without substantial intervening condensation thereof, fractionating the blended products in a 5 products fractionating zone, withdrawing a high boiling fraction from said products fractionating zone, said high boiling fraction being composed primarily of components substantially above the gasoline boiling range, subjecting said fraction to 10 a further cracking or conversion, introducing fluid products of such conversion back into the said products fractionating zone, and withdrawing as desired product a light fraction which comes within the motor fuel range from said 15 fractionating zone.

2. In the production of lower boiling hydrocarbons from a wide boiling range charge composed largely of higher boiling hydrocarbons, the process steps comprising dividing said charge 20 into at least two fractions of different boiling ranges, a lower boiling fraction and a higher boiling fraction, said lower boiling fraction being composed to substantial extent of components at least as high boiling as gasoline, passing said higher boiling fraction through a catalytic reaction zone containing an adsorptive contact mass capable of effecting transformation thereof to substantial extent into lower boiling hydrocarbons of the gasoline type, said catalytic 25 reaction zone being maintained under conditions which favor said transformation, passing said lower boiling fraction through a pyrolytic conversion zone while maintaining said fraction under conditions suitable for pyrolytic conversion 30 to produce high anti-knock motor fuel of the gasoline type, fractionating products of said pyrolytic conversion together with products of said catalytic transformation in a common products fractionating zone, withdrawing from the 35 latter a motor fuel product comprising a blend of pyrolytically and catalytically converted products, withdrawing also from said fractionating zone a stream of partially converted hydrocarbons higher boiling than said blended motor 40 fuel product, subjecting said stream to pyrolytic conversion conditions to produce therefrom further amounts of pyrolytic products having the boiling range of said motor fuel, and returning products of said last named pyrolytic conversion 45 to said fractionating zone to be fractionated 50 therein along with the other conversion products.

3. In the production of lower boiling hydrocarbons within the gasoline boiling range from a higher boiling hydrocarbon charge having a wide boiling range, the steps which comprise dividing the charge into at least two fractions of different boiling ranges, a lower boiling fraction and a higher boiling fraction, said lower boiling fraction being composed at least to substantial 60 extent of components above the gasoline boiling range, passing said higher boiling fraction through a catalyst reaction zone maintained under conditions capable of effecting a cracking of such fraction into lower boiling hydrocarbons, 65 said reaction zone containing solid catalytic material capable of promoting the said cracking, passing said lower boiling fraction through a pyrolytic conversion zone while maintaining such fraction under temperature and pressure conditions of pyrolytic conversion so as to effect a 70 substantial transformation or conversion thereof into high octane hydrocarbons within the gasoline boiling range, fractionating fluid products of both the catalytic and pyrolytic conversions in 75

5 a products fractionating zone, withdrawing therefrom a side stream fraction having boiling range characteristics substantially similar to those of the aforesaid lower boiling fraction of the original charge, sending said side stream fraction from the products fractionator along with said lower boiling fraction of the original charge to the aforementioned pyrolytic conversion zone, and withdrawing as desired final product from 10 said fractionating zone a light fraction composed at least largely of components within the gasoline boiling range, said light fraction comprising a blend of catalytically and pyrolytically cracked hydrocarbons of good chemical stability and high 15 anti-knock rating.

4. In the production of a light motor fuel comprising gasoline from crude petroleum oil having a wide boiling range and composed predominantly of hydrocarbons boiling above the range of the 20 desired light motor fuel product, the steps which comprise dividing such charge into straight-run gasoline, a residual fraction and a side stream fraction which is lower boiling than said residual fraction but higher boiling than gasoline, 25 passing said side stream fraction through a pyrolytic conversion zone while maintaining the same under pyrolytic conversion conditions so as to effect a cracking thereof to substantial extent into hydrocarbons within the gasoline boiling 30 range, passing the said residual hydrocarbon fraction through a catalytic cracking zone containing a catalyst comprising an active, adsorptive blend of silica and alumina and maintained under conditions capable of effecting conversion 35 of a substantial proportion of said residual fraction into hydrocarbons within the gasoline boiling range, flowing fluid hydrocarbon products from the catalytic and pyrolytic cracking zones, substantially in vapor phase, into a products 40 fractionating zone, fractionating the resulting products within said products fractionating zone, withdrawing a high boiling fraction from said products fractionating zone, subjecting at least the major proportions of the last-mentioned 45 fraction to pyrolytic conversion, cooling products of the last-mentioned conversion by heat interchange with the aforementioned whole crude petroleum oil charge and then passing products so cooled into the aforementioned products fractionating zone, withdrawing a fraction composed 50 predominantly of components within the gasoline boiling range from said products fractionating zone, and blending the last-mentioned fraction with the aforesaid straight-run gasoline from the original crude petroleum charge so as to form the desired light motor fuel product.

5. In the production of lower boiling hydrocarbons from higher boiling hydrocarbon charge of wide boiling range, the steps which comprise 60 dividing the charge into at least two fractions of different boiling ranges, a lower boiling fraction and a higher boiling fraction, said lower boiling fraction being composed, at least in substantial part, of hydrocarbon components above the gasoline boiling range, passing said higher boiling fraction through a catalytic reaction zone maintained under conditions capable of effecting a 65 transformation thereof into lower boiling hydrocarbons of high anti-knock rating, said catalytic reaction zone containing solid adsorptive silicious catalytic material capable of promoting the said transformation, withdrawing fluid products of reaction from said catalytic reaction zone and condensing and separating a portion of the 70 higher boiling components of such products as

condensate from remaining lower boiling vaporous components, passing the aforesaid lower boiling fraction of the original charge through a pyrolytic conversion zone while maintaining such fraction under temperature and pressure conditions of pyrolytic conversion so as to effect a substantial transformation thereof into good anti-knock components within the low boiling motor fuel range, passing products from said pyrolytic conversion zone into a cooling zone and 10 continuously introducing the aforesaid condensate, separated from the products from said catalytic conversion zone, into said cooling zone and into contact with pyrolytic products to arrest pyrolytic reactions, sending pyrolytic products from said cooling zone and the aforementioned vaporous components of the products from said catalytic conversion zone into a products fractionating zone, and withdrawing from said products fractionating zone a lower boiling hydrocarbon fraction composed predominantly of components within the gasoline boiling range, thereby economically to produce a desired light motor fuel comprising a blend of catalytically and pyrolytically cracked hydrocarbons. 15

6. In the production of lower boiling hydrocarbons, including components within the gasoline boiling range, from a higher boiling hydrocarbon charge, the steps which comprise dividing the charge into at least two fractions of different 20 boiling ranges, a lower boiling fraction and a higher boiling fraction, said lower boiling fraction being composed at least to substantial extent of components higher boiling than gasoline, passing said higher boiling fraction through a 25 confined zone containing an active silicious catalyst under conditions capable of effecting a cracking thereof into lower boiling hydrocarbons, passing said lower boiling fraction through a pyrolytic conversion zone while maintaining such 30 fraction under desired pyrolytic conversion conditions so as to effect a cracking or transformation of a substantial proportion thereof into low boiling hydrocarbons in the light motor fuel or gasoline boiling range, passing vaporous products 35 of the catalytic and pyrolytic conversions, without substantial preliminary condensation thereof, into a products fractionating zone, fractionating the resulting blended products in said products 40 fractionating zone, withdrawing as desired product a light fraction which comes within the motor fuel range from said fractionating zone, withdrawing as a side stream from said products fractionating zone a fraction composed primarily 45 of components within the gas oil boiling range and capable of being readily converted into gasoline, and withdrawing a fraction from said fractionating zone, adjacent the bottom thereof, cooling a portion of said last-named fraction and 50 returning the same to said products fractionator at a level above that from which it was withdrawn so as to maintain the temperature of the bottom of the products tower within the preferred 55 range in order to control the boiling range characteristics of said light fraction or desired motor fuel product within desired limits.

7. Apparatus for producing a motor fuel composed of a blend of catalytically and pyrolytically converted products from a crude hydrocarbon 60 charge comprising a fractionator for crude charge, a converter having a reaction chamber, a solid adsorptive catalyst in said reaction chamber, fluid conducting means joined between a point toward the bottom of said fractionator and 65

- said converter for conducting charge from the former to the latter, a products tower for fractionating products of conversion, a fluid conduit leading from said converter to a point intermediate the ends of said tower to transfer products of reaction from the former to the latter, a pyrolytic reaction chamber or converter, a duct for passing a lower boiling fraction from said fractionator for charge to said pyrolytic reaction chamber, a conduit for passing products of reaction from said pyrolytic reaction chamber to said products tower, a second pyrolytic converter, means including a duct for passing a fraction substantially higher boiling than gasoline from 5 said products fractionator to said second pyrolytic converter, a duct for returning products of reaction from said second pyrolytic converter to a point in said products tower intermediate the ends thereof, means for effecting transfer of heat 10 from products of conversion to charge or portions thereof before the same undergoes conversion, and a lead off adjacent the top of said products tower for withdrawing desired low boiling motor fuel product.
- 20 8. Apparatus for producing a low boiling motor fuel composed of a blend of catalytically and pyrolytically converted products from a crude hydrocarbon charge comprising a fractionator for crude charge, a catalytic conversion system comprising a heater for heating charge to the system at reaction temperature and a catalytic converter following and connected to said heater, said converter having a reaction chamber, a solid adsorptive siliceous catalytic material in said reaction chamber, fluid conducting means joined between a point toward the bottom of said fractionator and said heater for conducting charge from the former to the latter, a products tower for fractionating products of conversion, a fluid 30 conduit leading from said converter to a point intermediate the ends of said tower to transfer products of reaction from the former to the latter, a pyrolytic reaction chamber or converter, a duct for passing a lower boiling fraction from said fractionator for charge to said pyrolytic reaction chamber, a conduit for passing products of reaction from said pyrolytic reaction chamber to said products tower, means including a duct for passing a fraction substantially higher boiling than gasoline from 35 said products fractionator to said pyrolytic reaction chamber, a conduit for passing products of reaction from said pyrolytic reaction chamber to said products tower, means including a duct for passing a fraction substantially higher boiling than gasoline from said products fractionator, a conduit for withdrawing a fraction from a point adjacent the bottom of said products fractionator, means for cooling at least a portion of the last-mentioned fraction, means for returning at least a portion of said last-mentioned fraction to said products tower toward the lower end thereof, thereby to provide for controlling the temperature of the lower end of said tower, and means adapted to withdraw a gasoline fraction from adjacent the top of said products tower to bring it into admixture with the fluid passing from the aforesaid fractionator for crude charge through the said duct for withdrawing straight-run gasoline, thereby to provide apparatus for the production of a desired blend of straight-run and catalytically and pyrolytically cracked gasolines.
- 40 9. Apparatus for producing a motor fuel, or gasoline composed of a blend of catalytically and pyrolytically converted products from a crude hydrocarbon charge comprising a fractionator for crude charge, a converter containing an active catalyst, fluid conducting means joined between a point toward the bottom of said fractionator and said converter for conducting charge from 45
- 50
- 55
- 60
- 65

the former to the latter, a partial condensing means, a fluid lead from said converter to said partial condensing means, a products tower for fractionating products of conversion, a fluid conduit leading from said partial condenser to a point intermediate the ends of said tower for passing products in vapor form, freed of condensed higher boiling components, from the former to the latter, a pyrolytic reaction chamber or converter, a duct for passing a lower boiling fraction from said fractionator for charge to said pyrolytic reaction chamber, a quenching chamber, a fluid lead for passing fluid products from the said pyrolytic reaction chamber to said quenching chamber, means including a conduit 15 for passing condensed portions of the products of catalytic conversion from the aforesaid partial condensing means into said quenching chamber, a duct for passing fluid from the latter chamber to a point in said products tower intermediate the ends thereof, means including a duct for passing a fraction substantially higher boiling than gasoline from said products fractionator so that the same may be further converted, and a lead off adjacent the top of said products tower for withdrawing desired gasoline products.

25 10. Apparatus for producing a motor fuel or gasoline of controlled and high grade characteristics composed of catalytically and pyrolytically converted products from a crude petroleum oil or hydrocarbon charge comprising a fractionator for crude charge, a duct for withdrawing straight-run gasoline from said fractionator, a converter adapted to contain a catalyst, fluid conducting means joined between a point toward the bottom of said fractionator and said converter for conducting charge from the former to the latter, a products tower for fractionating products of conversion, a fluid conduit leading from said converter to a point intermediate the ends 30 of said tower to transfer products of reaction from the former to the latter, a pyrolytic reaction chamber or converter, a duct for passing a lower boiling fraction from said fractionator for charge to said pyrolytic reaction chamber, a conduit for 35 passing products of reaction from said pyrolytic reaction chamber to said products tower, means including a duct for passing a side stream fraction which is higher boiling than gasoline from said products fractionator, a conduit for withdrawing a fraction from a point adjacent the bottom of said products fractionator, means for cooling at least a portion of the last-mentioned fraction, means for returning at least a portion of said last-mentioned fraction to said products tower toward the lower end thereof, thereby to provide for controlling the temperature of the lower end of said tower, and means adapted to withdraw a gasoline fraction from adjacent the top of said products tower to bring it into admixture with the fluid passing from the aforesaid fractionator for crude charge through the said duct for withdrawing straight-run gasoline, thereby to provide apparatus for the production of a desired blend of straight-run and catalytically and pyrolytically cracked gasolines.

CERTIFICATE OF CORRECTION.

Patent No. 2,197,008.

April 16, 1940.

ARTHUR E. PEW, JR.

It is hereby certified that error appears in the printed specification of the above numbered patent requiring correction as follows: Page 5, first column, line 1, claim 3, before the word "products" insert --common--; and that the said Letters Patent should be read with this correction therein that the same may conform to the record of the case in the Patent Office.

Signed and sealed this 4th day of June, A. D. 1940.

(Seal)

Henry Van Arsdale,
Acting Commissioner of Patents.
